WITNESS:

John Donovan

UNITED STATES PATENT OFFICE.

RICHARD DEAN KENNEDY, OF ALTOONA, PENNSYLVANIA.

DIAL.

Application filed November 28, 1925. Serial No. 72,009.

The object of this invention is to provide an improved dial for use on an automatic telephone, and especially designed to facilitate the use thereof at night.

6 A further object is to provide a special construction including a plurality of split discs, each having laterally extending ears adapted to project on opposite sides of the finger hook, one of the discs carrying illuminated characters, and the other being transparent and acting as a protecting device, the two discs when secured together being mounted below the usual element having finger holes therein.

15 With the foregoing and other objects in view, the invention consists in the novel construction and arrangement of elements described, illustrated and claimed, it being understood that modifications may be made 20 within the scope of the claim, without departing from the spirit of the invention.

In the drawings forming part of this application,

Figure 1 shows the construction in top 25 plan.

Figure 2 is a view in front elevation.

Figure 3 is an elevation of one of the split discs detached.

Figure 4 is a section on line 4—4 of Figure 3.

Figure 5 is a section on line 5—5 of Figure 3.

A disc 10 is provided with finger holes 11, and is mounted in spaced relation with reference to the special discs 11 and 12 herein disclosed. A finger hook 13 serves the usual purpose, and the discs are so formed that they have a particular relation with reference to the portion 14 of hook 13 and constituting the mounting member thereof.

The disc 11 has the form of a split ring, and includes the ears 15 and 16, each provided with an eyelet hole 17 for the accom-

modation of eyelet 18, to be applied through both discs, as indicated below. This disc 45 11 is of celluloid or other transparent material, and acts as a protecting device for disc 12, immediately adjacent thereto, and carrying the numbers or characters to be read. Disc 12 may also be of celluloid, and the 50 characters 12', thereon are coated with a radium compound, or are formed thereof. Disc 12 is also provided with ears adjacent to the split ends, the ears corresponding with elements 15 and 16 of the other disc, and 55 apertures being provided for eyelet 18.

Ears 15 and 16 of the discs therefor register, when connected by eyelet, and these elements 15 and 16 pass on opposite sides of the finger hook 13 and are retained by passing a 60 short length of copper wire or other suitable securing device through the eyelet. The combined discs 11 and 12 are therefore securely retained, and may be applied with the least possible difficulty, the split portions 65 facilitating the work of placing the device in position with reference to the portion 19 of the instrument. The device may likewise be readily detached, and removed to another instrument, if desired.

What is claimed is:

An attachment for an automatic telephone including an apertured finger disc, and a finger hook, said attachment comprising a plurality of split discs having laterally extending ears adapted to project on opposite sides of the hook, one of the split discs carrying illuminated characters, and the other split disc constituting a transparent protecting element, and means for connecting 75 80 85 adjacent ears of the discs, these ears overlapping each other, and means connecting the oppositely located ears and passing around the hook.

In testimony whereof I affix my signature.

RICHARD DEAN KENNEDY.
